US00D869830S

(12) **United States Design Patent** (10) Patent No.: **US D869,830 S**
(45) Date of Patent: **** Dec. 17, 2019**

(54) **SHOE**

(71) Applicant: **adidas AG**, Herzogenaurach (DE)

(72) Inventors: **Timothy David Lucas**, Herzogenaurach (DE); **Gerd Rainer Manz**, Oberreichenbach (DE); **Jan Hill**, Großenseeback (DE); **Paul Leonard Michael Smith**, Nürnberg (DE); **John Whiteman**, Nürnberg (DE)

(73) Assignee: **adidas AG**, Herzogenaurach (DE)

(**) Term: **15 Years**

(21) Appl. No.: **29/610,003**

(22) Filed: **Jul. 7, 2017**

Related U.S. Application Data

(63) Continuation of application No. 15/280,800, filed on Sep. 29, 2016, which is a continuation of application No. 15/155,722, filed on May 16, 2016, which is a continuation of application No. 14/937,640, filed on Nov. 10, 2015, now Pat. No. 9,339,079, which is a (Continued)

(57) **CLAIM**

The ornamental design for a shoe, as shown and described.

DESCRIPTION

The FIGURE is a side view of a shoe showing the claimed design.

The dashed broken lines in the FIGURE show portions of the shoe that form no part of the claimed design.

The dot-dash broken lines in the FIGURE and the area(s) within the dot-dash broken lines show portions of the shoe that form no part of the claimed design.

1 Claim, 1 Drawing Sheet

Related U.S. Application Data

continuation of application No. 12/967,974, filed on Dec. 14, 2010, now Pat. No. 9,345,285.
